UNITED STATES PATENT OFFICE.

VIRGIL M. PRICE, OF SAN FRANCISCO, CALIFORNIA.

CONCRETE-MIXER LOADER.

1,424,737.

Specification of Letters Patent. Patented Aug. 1, 1922.

Application filed January 6, 1920. Serial No. 349,737.

To all whom it may concern:

Be it known that I, VIRGIL M. PRICE, a citizen of the United States, residing at San Francisco, in the county of San Francisco and State of California, have invented certain new and useful Improvements in Concrete-Mixer Loaders; and I do hereby declare the following to be a full, clear, and exact description of the invention, such as 5 will enable others skilled in the art to which it appertains to make and use the same.

This invention relates to a machine intended especially for facilitating the loading of concrete mixers with sand, cement 15 and rock or gravel, and is particularly an improvement over the concrete mixer loader disclosed in Patent No. 1,340,345 granted May 18, 1920.

The invention has for its object the provision of a novel arrangement as over the construction disclosed in said patent, whereby to simplify the loader, and to enhance the utility and efficiency thereof.

Another object is the provision of such a 25 loader having bins for receiving the materials, such as cement, sand, rock and gravel, means for elevating the materials to discharge them into the bins and a novel arrangement for directing the material into 30 the proper bin.

A further object is the provision of novel discharge means for the bins whereby to deliver the material into the hoisting loading skip of a concrete mixer.

35 A still further object is to operatively connect the loader and mixer whereby one is pulled or drawn by the other from place to place and providing a novel cooperative relation between the delivery or discharging means of the bins and the hoisting loading skip of the concrete mixer in order that the material can be delivered to the skip in measured quantities and prepared for delivery to the mixer during 40 the operation of the mixer.

With the foregoing and other objects in view, which will be apparent as the description proceeds, the invention resides in the construction and arrangement of parts 45 hereinafter described and claimed it being understood that changes can be made within the scope of what is claimed without departing from the spirit of the invention.

The invention is illustrated in the accompanying drawings, wherein:

Figure 1 is a side elevation of the con-

crete mixer and the loader, portions being broken away.

Fig. 2 is an enlarged plan view of the loader showing the hoisting loading skip of 60 the mixer in section.

Fig. 3 is a rear view of the loader.

Fig. 4 is an enlarged vertical section 65 through one of the gates and discharge chutes of the bins.

In carrying out the invention, there is provided a suitable vehicle frame 1 mounted upon the front wheels 2 and the rear propelling wheels 3, and carrying a suitable internal combustion engine 4. The vehicle or wheel is preferably self-propelled by the engine, the wheels 2 forming a part 70 of suitable steering gear, and the wheels 3 being operatively connected, as at 5, to the engine.

75 The loader can be used with various concrete mixers, a typical mixer being shown, and it comprises the frame 6 mounted on the wheels 7 and carrying the mixer 8. The frame work 10 carries a swinging arm 11 to 80 which is secured the hoisting loading skip 12, which is elevated by one or more cables 13 passing over a guide roller 14 and wound upon a drum 15. The skip 12 has a pan-shaped portion to rest on the ground when 85 the skip is swung downwardly as seen in Fig. 1, and said pan is extended into a spout 18, which when the skip is raised will register with the filling spout 19 of the mixer 8, so that the material will gravitate 90 from the skip through the spout 18 into the mixer. The pan-portion of the skip has a longitudinal partition 17 dividing said skip into receptacles for sand and gravel or rock in which such materials can be measured 95 and the cement then added.

The loader and mixer are connected by draw bars 9, whereby the mixer will be pulled by the loader so that they remain coupled together for cooperation during 100 movement as well as when at a standstill, and the bars 9 serve to support the skip when it is lowered to receive the material.

The framework 16 of the frame 1 has mounted therein a pair of bins or hoppers 105 22 and 23 disposed side by side, and having a common partition 23^a separating them, and the bottom wall of said bins slope to the rear wall which is provided adjacent to the bottom with a discharge opening 24' for 110 each bin normally closed by a vertically slid able gate or valve 24.

In order to conveniently deliver crushed rock, gravel and sand into the bins, an inclined runway or incline 25 is carried by the forward portion of the frame 1 and frame work 16, and its upper end curves over and overhangs, as at 26, bins 22 and 23. The lower portion of the incline is widened and has a loose section 27 pivoted, as at 28, to the lower end of the incline and 10 curved from the incline toward the horizontal away from the machine, and the portion 27 is provided with wheels or rollers 29 at the opposite sides to rest on the ground and thus support the lower edge of the 15 portion 27, in proper relation to the ground. The portion 27 can swing upwardly and downwardly according to the unevenness of the ground.

Mounted on the upper portion of the 20 frame work 16, above the upper end of the incline 25, is a transverse drum 30 carried by a shaft 30', which is operatively connected by a vertical shaft 31 with the engine, and a cable 32 is connected to said drum to be 25 wound thereon and unwound therefrom. The free end of this cable 32 is connected to the bail 33 of a scoop 34, and a clutch 38 is provided between the drum 30 and shaft 30' for connecting said drum to and disconnecting it from the engine, at the will of 30 the operator. By opening the clutch, the cable 32 can be unwound for pulling the scoop away from the loader behind a pile of sand, gravel or rock, and by throwing the 35 clutch in, the cable will be wound upon the drum for pulling the scoop to and up the incline.

The scoop when pulled to the upper end 40 of the incline discharges over said upper end of the incline and over the longitudinal partition 23^a, and in order to direct the material into the proper bin, a longitudinal chute or wing 35 is hinged, as at 36, to the upper edge of the partition 23^a, and can be swung toward one side or the other according to the 45 material being elevated. The bin 22 is for holding rock or gravel, and the bin 23 for holding sand, so that when the rock or gravel is being elevated, the wing 35 is swung over 50 the bin 23, as seen in dotted lines in Fig. 3, thereby deflecting the rock and gravel into the bin 22. When sand is being elevated, the chute 35 is swung over the bin 22, as seen in full lines in Fig. 3, thereby deflecting the 55 material into the bin 23. Referring to Fig. 3, the chute 35 is supported in dotted line position by one side of the frame, and is supported in full line positions by means of a stop or bracket 45 carried by the frame- 60 work 16 at the opposite side.

A transverse roller 39 is preferably provided over the lower end of the incline 25 being carried by braces 40 secured to and extending upwardly from the sides of the incline, and the cable 32 passes under the roller

39, whereby to facilitate the pulling of the scoop to the lower end of the incline and up over the entrance portion 27 to pass up the incline.

A transverse bumper bar 43 is carried by 70 springs 44 by the framework 16 above the upper end of the incline, to cushion the scoop 34 when it is pulled to the upper end of the incline and swung upwardly to dumping position, as seen in dotted lines in Fig. 1. 75

The gates 24 have means for raising and lowering them, and for this purpose, said gates have rack teeth 46 meshing with pinions 47 on transverse shafts 48 having hand wheels 49, which when turned will raise or lower said gates to control the flow and discharge of material from the bins. Said bins have discharge spouts 50 extending from the rear wall thereof to deliver the material 80 from the openings 24'. 85

In order to direct the material from the spouts 50 into the receptacles of the skip 12, delivery chutes 51 are provided, one for each spout 50 and said chutes 51 are pivoted, as at 52, upon hinge leaves 53 mounted for vertical movement upon a transverse rod 54. The chutes 51 can thus be swung on the pivots 52 sidewise, to deliver the material into the respective receptacles of the skip 12, and to spread the material in such 95 receptacles, and the hinge rod 54 enables the chutes 51 to be swung upwardly and downwardly with the leaves 53. In this way, the chutes can be swung upwardly against the back of the bins out of the way, 100 and can be readily lowered to discharge the material by gravity to the skip.

Cables 55 are connected to said chutes 51 and pass over rollers or pulleys 56 carried by the bins and counterweights 57 are connected to said cables for raising the chutes 51 and holding them in raised position when not in use. 105

In operation, the scoop 34 is used for conveying the material from piles to the loader 110 and for elevating the material to discharge it into the bins. Thus, when the clutch 38 is opened, the cable 32 can unwind to enable the scoop 34 to be moved behind a pile of sand, rock or gravel, and then by throwing 115 in the clutch, the cable will be wound up to pull the scoop to the incline, thereby filling the scoop and moving it to the loader and up the incline 25.

When the scoop reaches the upper end of 120 the incline, it is raised, being stopped by the bumper bar 43, and the material is dumped into the bins. If sand is being carried by the scoop, the chute 35 is swung against the bracket 45 so that the sand in dropping 125 onto said chute will be delivered into the bin 23, whereas if rock or gravel is being carried by the scoop, the chute 35 is swung toward the opposite side. This operation is repeated to feed the material into the bins, 130

and the chute 35 is swung back and forth so that the materials are delivered to the proper bins, and this operation can be repeated and continued during the operation 5 of the mixer without interruption.

To deliver the material to the mixer, the skip 12 is lowered, so that the pan thereof rests on the bars 9, and the chutes 51 are then swung downwardly and are swung 10 transversely so as to project over the proper receptacles of the skip pan. Then, by opening the gates 24, the material will be discharged through the spouts 50 and will flow down the chute 51 into the skip, and such 15 materials can be measured in the skip by suitable graduations therein, and the flow can be shut off when the proper amounts have been delivered into the skip. The cement is then added to the skip, and by winding 20 the cables 13 on the drum 15, the skip 12 is swung upwardly, the chutes 51 being thereby swung upwardly out of the way, and the spout 18 being brought into registration with the mixer spout 19, so that the material 25 will be dumped into the mixer. Then, during the operation of the mixer, the skip 12 can be returned and the chutes 51 swung downwardly over the skip, so that the skip can be loaded during the mixing of the previous 30 charge, whereby the mixer can be re-filled as soon as emptied, this operation being repeated, and the bins containing a sufficient supply of material so that no delay results in mixing the batches of concrete. 35 The bins can thus be filled during the operation of delivering the material to the skip and from the skip to the mixer, and the two operations can be carried on simultaneously without interference or interruption, thereby avoiding delays and saving time as well as labor.

Having thus described the invention, what is claimed as new is:—

1. A concrete mixer loader comprising a frame, bins mounted on said frame side by side and having a longitudinal partition between them, said bins having rear discharge openings and gates, means for elevating materials and dumping same over 45 said partition, a longitudinal chute hinged on said partition and adapted to be swung toward opposite sides for directing the ma-

terial into one bin or the other, and means for receiving the materials from all of said 55 discharge openings for delivering same to a mixer.

2. The combination of a concrete mixer having a hoisting loading skip to move upwardly and downwardly, a loader having 60 bins for holding different materials and means for delivering such materials to the skip when the skip is lowered, and means connecting the mixer and loader for the movement of one with the other and arranged to support said skip in position to receive the materials.

3. The combination of a concrete mixer having a hoisting loading skip to move upwardly and downwardly, a loader having 70 bins for different materials and means for delivering such materials to said skip when the skip is lowered, and draw bars connecting the mixer and loader for moving one with the other and arranged to support said 75 skip in lowered position for receiving the materials.

4. The combination of a concrete mixer having a hoisting loading skip, a loader having bins for different materials and 80 means for delivering the materials to said skip when it is lowered, and draw bars connecting said mixer and loader for moving one with the other and for supporting said skip when it is lowered, said draw bars being offset downwardly between their ends to slide and rest on the ground.

5. A concrete mixer loader comprising bins for different materials having delivery 90 openings and chutes for controlling the delivery of said materials, spouts extending from said openings, a transverse hinge rod extending under said spouts, hinged members mounted on said rod under the spouts to swing upwardly and downwardly, and 95 chutes extending across said members from under the spouts and pivoted on said members to swing sidewise.

In testimony whereof I have signed my name to this specification in the presence of 100 two subscribing witnesses.
